UNITED STATES PATENT OFFICE

JULIUS KASS, OF NEW YORK, N. Y.

PORTABLE DISPLAY STAND

Application filed April 2, 1931. Serial No. 527,097.

This invention relates to improvements in display apparatus and has particular reference to a portable stand for displaying clothing and the like.

5 An object of the invention is to provide an improved stand of simple, practical and inexpensive construction, by means of which clothing may be stored and displayed with a minimum handling thereof, and in which the 10 clothing will be protected against the accumulation of dirt and damage by moths.

The above and other objects will appear more clearly from the following detailed description, when taken in connection with the 15 accompanying drawings, which illustrate preferred embodiments of the inventive idea.

In the drawings—

Figure 1 is a perspective view of one form 20 of stand, parts being broken away;

Figure 2 is a vertical transverse section of the stand shown in Figure 1;

Figure 3 is an elevation of a detail;

Figure 4 is a view similar to Figure 1, showing a collapsible construction of stand;

Figure 5 is a similar view showing the stand in its collapsed condition; and

Figure 6 is an enlarged fragmentary sectional view of the framework of the stand, showing the manner in which the elements 30 thereof are assembled.

Referring more particularly to Figures 1 to 3, the stand shown therein is especially adapted for use in large wholesale dress establishments wherein it becomes necessary

35 to display quite a number of dresses to buyers who generally order by lots. The stand is shown as comprising a framework, the elements of which are all made of metal tubing and which includes the upper and lower rectangular frames 10 and 11 joined at their ends by standards 12 and 13 which have T-couplings 14 through which the ends of said frames are extended when assembling the framework.

40 Adjacent the upper ends of the standards 12 and 13 the same are connected by a clothing-supporting bar 15 from which dresses and the like are suspended by the usual hangers 16. The lower frame 11 is provided at its corners with casters 17 which enable the stand to be easily transported from

place to place, and resting upon said frame is a cover plate 18 notched at each end, as indicated at 19, to receive the lower ends of the standards whereby the plate is held from becoming dislodged. The central portion of 55 the plate 18 is provided with a plurality of perforations 20 and below these perforations there is supported a receptacle 21 for containing an insecticide, such as moth balls or the like. An inlet opening 22 for the receptacle is provided in the plate 18 while an outlet opening 23 is formed in the bottom of the receptacle. Closures 24 and 25 are provided for the respective openings 22 and 23 whereby moth balls or the like may be inserted into the receptacle and removed therefrom.

The upper frame 11 supports a cover plate 26, the marginal edges of which are formed with a continuous flange 27 depending from 70 the plate and engaging the frame 10 so as to prevent lateral displacement of the plate. Said flange 27 is bent upwardly to form a guide channel 28 for receiving a plurality of hooks 29 secured at intervals along the top 75 edge of a flexible curtain 30 which, when in closing position, is adapted to entirely encircle the framework and thus form a protective covering for the clothing supported upon the bar 15. When displaying the contents 80 of the stand, the ends of the curtain may be forced back along one end of the plate 26 and both sides thereof, the hooks 29 then sliding in the guide channels.

If desired, a small dome light 31 may be mounted in a small dry cell battery-receiving receptacle 32 carried by the under surface of the plate 26. A further accessory, in the form of a small writing table 33, may be 85 hinged to the standard 12 and supported by the hinged connections 34 which will permit of the table being adjusted to a horizontal operative position, or swung to a vertical position alongside of the standard when not in 90 use.

The display stand shown in Figures 4 to 6 is smaller in size than the one above described and is made so that it can be collapsed when not in use. Here, again, the framework of 100

the stand is formed of tubing and includes the upper and lower frames 35 and 36 supporting, respectively, the cover plates 37 and 38. The frames 35 and 36 are connected by 5 two standards, each comprising a plurality of sections 39. Each section is screw-threaded at its ends to engage in couplings 40 and the upper and lower sections of each standard are threaded into couplings 41 carried by the respective frames. A clothing-supporting bar 42 is detachably connected to the uppermost sections of the standards and forms a means for suspending clothing therefrom.

The lower frame 36 is provided with casters 43 and the central portion of the cover plate 38 resting upon said frame has suspended therefrom a receptacle 44 in all respects similar to the receptacle 21.

The upper plate 37 is provided with a marginal depending flange 45 and bent to provide a continuous guide channel extending about the edges of the plate and adapted to receive hooks 46 of the flexible curtain 47 which extends completely about the framework when in enclosing position and which can be detached from the plate and folded, as indicated in Figure 5, when the stand is collapsed. As shown in Figure 5, the upper frame 35 and its plate 37 may be rested upon 10 the lower plate 38 and the various sections 39 of the standards and the supporting bar 42 may be placed upon the plate 37 when the stand is not in use.

What is claimed is:

35. 1. A stand comprising upper and lower frames, standards connecting said frames, clothing-supporting means carried by said standards, cover plates for said upper and lower frames, the lower plate having perforations therein, a flexible curtain suspended from the edges of said upper plate, and a receptacle mounted on the underside of the lower plate adjacent said perforations, said receptacle having an inlet and an outlet opening, said inlet opening being formed in the lower plate and the outlet opening being in the bottom of said receptacle, and closures for 40 said openings.

50. 2. A stand comprising upper and lower frames, standards connecting said frames, clothing-supporting means carried by said standards, a cover plate for said upper frame, another cover plate for said lower frame, the 55 upper cover plate having a guide flange extending completely around its edge, the lower cover plate having perforations therein, a plurality of hooks suspended from the edges of said guide flange and slidably thereon, a flexible curtain connected with said hooks, a 60 receptacle mounted on the underside of the lower cover plate adjacent said perforations, said receptacle having an inlet and an outlet opening, said inlet opening being formed in 65 the lower cover plate and the outlet opening

being in the bottom of said receptacle, and closures for said openings.

In testimony whereof, I have affixed my signature.

JULIUS KASS.
